UNITED STATES PATENT OFFICE.

VITTORIO BETTELONI, OF FLORENCE, ITALY.

COMPRESSED-AIR WATER ELEVATOR.

Application filed October 22, 1920. Serial No. 418,779.

To all whom it may concern:

Be it known that VITTORIO BETTELONI, a subject of King of Italy, residing at Florence, Toscana, Italy, have invented new and useful Improvements in Compressed-Air Water Elevators, of which the following is a specification.

The invention forming the subject-matter of the present application is an improvement in the system of distributing the compressed air in hydraulic liquid-raising engines, which is described in the specification of British Patent #7290 of 1914, granted to Attilio Mariotti.

15 The accompanying drawing shows an example of an engine of this description with the corresponding application thereof. In the same, Fig. 1 is a side elevation of the apparatus as applied for working purposes; 20 Fig. 2 is a longitudinal section of the chest for the distribution of the compressed air; Fig. 3 is a transverse, sectional view taken approximately on the line 3—3 of Fig. 1, looking in the direction of the arrows, and 25 drawn to a very much larger scale than Fig. 1, and Fig. 4 is a detail of the motive gear attached to the driving shaft.

Fig. 1 shows the complete system in working order, with the suction pipes —a—b— 30 in communication with the two receptacles —c—d— immersed in the liquid to be raised. The two pipes —a—b— connect the two receptacles —c—d— with the distributing chest —e—. The two receptacles are furnished at their lower part with valves —c¹—d¹—; this allows the compressor to draw in the air from one of the two receptacles and to compress it in the other, in such manner that, of the two receptacles, the one 35 sustaining the pressure will tend to discharge its water, which will be driven into the outlet pipe —f— through one of the two valves —c²—d²—; thus the same receptacle will be emptied of water but filled with compressed 40 air. As soon as the receptacle has delivered its water, the passages in the air valve chest are reversed, so that, whereas, at first, suction was effected from one receptacle and compression in the other, the converse will 45 now occur, i. e. the compressed air will be drawn in from the receptacle already emptied of its water in order that it may be sent into the other receptacle, so that its liquid may, in its turn, be discharged and, in 50 the mean time, the first receptacle may be permitted to be filled with water.

The above mentioned reversion of the chest passages is brought about in the following manner; to the driving shaft —g— (Figs. 1 and 4) of the compressor is fitted 55 a worm *h*, gearing with a worm wheel *i* which conveys the motion of the shaft —g— to the axle —k—. Said axle —k— enters the box —l— fitted to the chest —e— and by means of the endless screw gearing —m— 60 imparts the motion to the toothed wheel —n— which, in its turn, acts on the cam —o—, which, by its rotation, imparts motion to a lever —p— of the first class. This lever —p— is pivoted to a small double piston —q— whose pistons —r—s— are equal in diameter and the pressure on which equilibrates said rod. The oscillation of the lever *p* effects a rapid reciprocation of the piston rod *q* at stated intervals, which, by 65 suitably proportioning the gearing, may be varied to suit the characteristic features of the working of the compressor. This is one system for obtaining motion of this description, but other means may be employed to 70 produce the same result and at the same time render it possible to locate the chest at any distance from the compressor.

Assuming, for instance, that the axis of the helical screw *m*, which moves the helicoidal wheel *n* and, therefore, the cam *o* likewise, receives its movement directly from a small electric motor, whose speed is well defined, instead of receiving its motion from the main shaft of the compressor by means 75 of the worm gearing *h*, *i*, manifestly the effect in respect of the functioning of the system is identical with that in the first instance; it is also plain that the speed of rotation of the cam *o*, besides being varied by 80 the regulation of the speed of the small motor, may also be varied by changing the number of teeth of the helicoidal wheel *n* or the number of the threads of the helical screw *m*, or also by the transmission of the motion of the cam *o* by several couples of screws and helicoidal wheels or of gearings, which gradually bring about the slackening 85 of the movement until a very slow motion is 90 imparted to the cam *o*.

The same may be said should it be desired to employ a small compressed air motor, viz: a small aeromotor (instead of a small electric motor), which by also acting on the axis of the helical screw, would transmit a rotary movement to the cam *o*. Both 95 in the case of the small electric motor and 100 aeromotor, the cam *o* may be actuated by 105 the rotation of the screw *m* or by the rotation of the helicoidal wheel *n*.

in that of the compressed air motor and in that of any other small motor it is, as has already been stated, possible to locate the distributing chest at a distance from the compressor.

By means of the longitudinal reciprocation alluded to, the small double piston g instead of being operated from the compressor assumes at given intervals of time 10 one of the two well defined positions in order to alternately close either the couple of orifices $t-u$ of the chest e (and, in this case, into the pipe a which is attached to the flange of the chamber y) 15 or is admitted the compressed air from the compressor and through the pipe b which is attached to the flange of the chamber v , is effected the suction of the compressor) or the couple of orifices $w-x$ of the same 20 chest e (and in this case through the pipe attached to the flange of the chamber y is effected the suction of the compressor and into the pipe attached to the flange of the chamber v is admitted the compressed air from the compressor itself.) 25

In order to allow of the compressed air which has been accumulating in one of the lower receptacles c, d passing as quickly as possible into the other receptacle to expel 30 therefrom the water which has been introduced into it meanwhile, the length of the pistons r, s of the small double piston is less than the width of the chamber y between the apertures t and x and of the chamber v between the apertures u, w , as shown in Fig. 35 2, the result thereby obtained being that during the reversing of the chest a part of the compressed air of one of the receptacles passes rapidly and directly from the chamber v into the chamber y , or vice-versa, without acting on the compressor piston, which is of great advantage in respect of the useful effect of the system and in ensuring the proper functioning of the compressor. Moreover, by the variation of the run of the 40 curve of the cam o it is possible, during the reversing motion of the small double piston to vary the time during which the direct discharge of the compressed air between the 45 two chambers y and v takes place.

The parts e and l form together a stuffing box for guiding the piston rod g

at one end thereof while the parts 2 and 3 form together another stuffing box for guiding said rod at its opposite end. In order 55 that the pistons r and s may be made perfectly airtight, by the closure of two of the orifices $t-u$ and $x-w$, the bores of which are all of the same diameter, all that is necessary, in cases where the degree of pressure is not very high, is that there shall be the least possible difference between the diameter of the orifices $t-u$ and $x-w$ and that of the pistons r and s , a difference of .01 of a millimeter 60 being sufficient. For very high degrees of pressure, the airtight fitting may be rendered more perfect by fitting the pistons r and s with packing rings. 65

The flanges 4 and 5 serve respectively for 70 the drawing in and expulsion of air from the compressor.

The auxiliary valve 6 allows of the compressor's suction also being taken from the atmosphere, that is, when the pressure 75 prevailing in the chamber 7 of the chest becomes lower than the atmospheric pressure.

Having thus described my invention, what I claim is:

A liquid raising apparatus, comprising in combination, an air compressor, a pair of receptacles having valve-controlled inlets for admission of the liquid to be raised, a distributing chest between the compressor and 80 said receptacles for alternately causing the air to be exhausted from one receptacle and compressed in the other and vice versa, said chest having a chamber in communication with each of the receptacles, a double piston 85 axially slideable in said chest for opening one of said chambers to compression and the other to exhaustion during a part of the operation of the compressor, and reversing such action during the remainder of said operation, and a cam operated by the compressor for reciprocating said double piston. 90

In testimony whereof I have signed my name to this specification.

VITTORIO BETTELONI.
